Filed Sept. 4, 1959, Ser. No. 57,448

Term of patent 7 years

(Cl. D31—4)

FIG. 7

FIG. 1

FIG. 4

FIG. 2

FIG. 5

FIG. 6

Figure 1 is a top perspective view of a fishing lure showing my new design;

Figure 2 is a top plan view thereof on an enlarged scale;

Figure 3 is a side elevational view thereof on an enlarged scale;

Figure 4 is an enlarged longitudinal cross-sectional view thereof taken substantially on the line 4—4 of Figure 2, looking in the direction of the arrows;

Figure 5 is an enlarged transverse cross-sectional view thereof taken substantially on the lines 5—5 of Figure 3, looking in the direction of the arrows;

Figure 6 is a bottom plan view thereof on an enlarged scale; and

Figure 7 is an enlarged, fragmentary view of the lure surface illustrating the hammered finish which covers the entire surface of the lure in Figures 1-6 inclusive.

The dominant features of my design reside in the full line portions of the drawing.

I claim:

The ornamental design for a fishing lure, as shown and described.
